UNITED STATES PATENT OFFICE.

FRANK R. BATCHELDER, OF WORCESTER, MASSACHUSETTS, ASSIGNOR TO MILLS BELT COMPANY, OF WORCESTER, MASSACHUSETTS, A CORPORATION OF MASSACHUSETTS.

CARTRIDGE-CARRIER.

1,374,712.

Specification of Letters Patent.

Patented Apr. 12, 1921.

Application filed August 5, 1918. Serial No. 248,252.

To all whom it may concern:

Be it known that I, FRANK R. BATCHELDER, a citizen of the United States, residing at Worcester, in the county of Worcester, State of Massachusetts, have invented a certain new and useful Improvement in Cartridge-Carriers, of which the following is a specification, reference being had therein to the accompanying drawings.

10 The invention relates to cartridge-carriers having, as in those of the waist-belt class, a plurality of cartridge-containing pockets arranged in line with one another horizontally, such pockets serving for the reception 15 of groups of cartridges held by clips. In practice, heretofore, the cartridge-containing pockets of carriers of such class have had the mouths or openings thereof located at the tops thereof so that the cartridges are 20 inserted into a pocket and removed therefrom by movement vertically. They have been furnished with covers for their open tops, such covers provided with fastenings, usually of the glove-fastener type, for securing 25 them in closed condition. Except in the case of the most favorably located pockets of the series of pockets of a waist-belt cartridge-carrier, the movements by which a cover is unfastened and thrown open and 30 the cartridges are removed from a pocket are somewhat inconvenient and are performed with a lack of ease and freedom, so that the action of the wearer in loading and reloading his gun is hindered and the rapidity 35 of firing affected. This has been more particularly observable in the case of the rear pockets of such belts, it being difficult for the wearer to reach around behind, undo the cover of one of such pockets, raise the 40 cover, and lift the cartridges vertically out of the pocket. This difficulty is experienced especially when the wearer is in the lying-down firing position. A leading object of the invention is to provide a pocket having 45 the mouth thereof so located that the drawback set forth above shall be obviated. The invention consists, essentially, in a cartridge-carrier having a series of pockets arranged in line with one another horizontally, with 50 the open mouth of each facing laterally so that in general the mouth of one thereof faces the adjacent end of the next pocket, and with the pocket-mouths respectively open from top to bottom of the pockets and

adapted for withdrawal of a clip of cartridges by a direct transverse movement from a pocket. The invention relates further to other features of cartridge-carriers and the like, and accordingly comprises other features of improved construction 60 which are described hereinafter and specified in the claims.

Illustrative embodiments of the invention are shown in the drawings, in which latter:—

65 Figure 1 shows a carrier embodying the invention, the pockets and their connection with the supporting-band or body-portions being shown somewhat conventionally.

Fig. 2 is an isometric oblique view of a portion of the supporting-band of a cartridge-carrier, and one pocket applied thereto in accordance with one illustrative embodiment.

Fig. 3 is a view similar to Fig. 2 but showing a pocket applied in accordance with a second illustrative embodiment of the invention.

Fig. 4 is a perspective view of a portion of a carrier, showing a form of retainer different from the form shown in Figs. 1 to 3.

Fig. 5 is a detail view showing a section of the retainer of Fig. 4 on line 5, 5.

The cartridge-carrier shown in Fig. 1 is of the waist-belt class, and in this instance 85 comprises opposite pocketed sections A, B, that are adjustably connected together at the rear by means of adjustment strap C engaged with gridirons D, D, which are attached to the rear ends of the said sections. 90 The front ends of the said sections are provided with belt-fastener members E, E', which are engaged with each other to connect the said ends together while the carrier is being worn. The body-band or belt- 95 portions of the two sections are marked a, b, respectively, and the pockets of the respective sections are marked a', and b'. Fig. 1 shows the cartridge-carrier in substantially the position in which it is worn, with the 100 pockets a', b', of each set in line with one another horizontally. It shows the feature of the open mouth, 1, of a pocket facing laterally so that in general the open mouth of one pocket faces the closed end 2, of the 105 next adjacent pocket, which has been mentioned already as a characteristic of the invention. As previously mentioned, the

open mouth of each pocket is open from top to bottom of the pocket, so as thereby to permit easy introduction of clips of cartridges into the pocket, and is adapted for 5 ready withdrawal of a clip of cartridges from the pocket by a direct transverse movement. Each pocket is shown furnished with a partition *c* serving to separate its interior space into two compartments, each 10 adapted to receive and contain a clip of cartridges. In this instance, the partition is diagonally disposed, so that thereby the said compartments are given reversely tapered forms to suit the shape of cartridges 15 inserted sidewise into the compartments and disposed reversely in the respective compartments of a pocket. The invention is not restricted with respect to the employment of a partition, its arrangement, or the 20 number of partitions provided in connection with a pocket. At 3 is a retainer in connection with the mouth of each pocket, comprising in this instance, as heretofore in some instances, a strip of webbing of convenient width which is fastened by one end thereof at the back of a pocket so that the retainer is adapted to be extended across the opening or openings of the mouth, from the rear to the front, the free end of the 25 retainer being adapted to be bent around against the front of the pocket, and such end being detachably secured to the said front by suitable fastener-devices 4, in this instance of ordinary snap-fastener type. 30 A feature of the cartridge-carrier shown in Fig. 1 is the fact that the mouths of all the pockets face toward the front, the sections *A*, *B*, being respectively right-hand and left-hand. This insures greater accessibility 35 of the said mouths and the pocket-contents.

The specific construction of a cartridge-carrier embodying the invention, and the mode of making the said cartridge-carrier, 40 may be varied more or less in practice.

Fig. 2 shows one mode of making the pockets and combining them with a supporting-band. This mode provides for producing woven pockets having at the side-opening of a pocket selvage-edges upon the front and back-walls, and upon the partition when a partition is provided. The pocket 45 shown in Fig. 2 is woven with its open mouth parallel with the warp-threads which are used in its fabrication. The weft or filling extends transversely of the pocket, and at the said mouth is returned upon itself in the margin of each of the web-portions constituting the pocket-front, the partition, the pocket-back, and the pocket-top, and pocket-bottom, so that said margins are produced as selvage-edges properly bound in the weaving. At the side opposite the 55 side-opening constituting the open mouth, 60 the warp-threads and weft or filling are

interwoven in any approved manner to produce a closed side. The novel method shown in Fig. 2 of attaching an applied pocket to a supporting-band involves as one feature thereof weaving the pocket-back with projecting portions or fins *d*², *d*², at its top and bottom ends for convenience in attaching the pocket to the supporting or body-band. In Fig. 2 these portions are shown as doubled back upon themselves, the 70 returned portions thereof being inserted into housing-slits which are formed for their reception in the top and bottom margins of the band. In this instance, the housing-slits are produced by the marginal portions 75 of the band being woven split or divided. The attachment to the said band is completed by means of horizontal lines of fastenings *e*, usually stitches, engaging with the said projecting fins, *d*², *d*², at the top 80 and bottom of the pocket, and also passing through the two side-walls of each housing-slit and the returned portion occupying the same, and also by vertical lines of fastenings *f*, *f*, usually stitches, passing 85 through marginal portions at the back of the pocket, at both sides of the latter. In practice, a number of pockets like that shown in Fig. 2 will be produced in a continuous web with the open mouth of a 90 pocket at one margin of such web, and with intermediate portions of web between the successive pockets so that when such intermediate portions are severed transversely 95 between one pocket and the next, to separate the pockets from one another, the parts of the said intermediate portions remaining attached to a pocket will constitute the fins *d*², *d*².

In Fig. 3 the web-continuations *d*³, *d*³, at 100 top and bottom of a pocket, here marked *b*³, are of sufficient length to extend around the top and bottom margins of the supporting-band and overlap at their ends, as at *d*⁴, the overlapping portions being fastened together suitably. Lines *e* and *f* of fastenings 105 are applied above and below the pocket, and at the sides thereof, as in Fig. 2.

In Figs. 2 and 3 the rear end of the retainer 3 is entered between the supporting-band and the back of the pocket, and made 110 secure by fastenings *g*, usually stitches.

Fig. 4 shows an improved form of retainer for a pocket having a side-opening. A retainer *3*^a of the form shown in Fig. 4 is 115 hinged by one end thereof to the forwardly-projecting top of a pocket, and is contrived so that when desired it may be swung up as at the left-hand side in such figure to thereby uncover the said side-opening, and 120 also so that it may be swung down alongside the side of the pocket so as to cover and close the side-opening, as at the right in Fig. 4. In this instance the retainer 3 is 125 constituted by a strip of webbing or other 130

suitable material having one end-portion thereof laid upon the projecting top of the pocket, and attached thereto by suitable fastenings h , such as stitches. The opposite end portion of the said strip is adapted to extend under and fit against the forwardly projecting bottom of the pocket, and usually is engaged therewith by suitable disengageable fastener means, such for instance as a snap-fastener, one member of which is shown at 4. The rear edge of the retainer fits against the face of the supporting-band sufficiently close to exclude rain and dust. If desired, a flange 3^b may be attached to the front portion of the retainer, to fit around the marginal portion of the face of the pocket when the retainer is closed down into place, as at the right in Fig. 4, to afford protection at the front. As shown in Fig. 4, the retainer constitutes an effective cover for the side-opening or mouth.

What is claimed as the invention is:—

1. A cartridge-carrier constructed to be worn in a horizontal position encircling the waist of the wearer, having a horizontal series of pockets each formed with a vertical mouth adapted for withdrawal of a clip of cartridges from the pocket by a transverse movement.
2. A cartridge-carrier constructed to be worn in a horizontal position encircling the waist of the wearer, having a horizontal series of pockets each formed with a vertical mouth adapted for withdrawal of a clip of cartridges from the pocket by a transverse movement, and furnished with detachable closure-means for the respective pockets.
3. A cartridge-carrier worn in a horizontal position, having a horizontal series of seamless woven pockets each formed with a vertical mouth, with the edges of the respective mouths bound in the weaving.

4. A cartridge-carrier worn in a horizontal position, having a horizontal series of seamless woven pockets composed of warp-threads disposed vertically and weft-threads disposed horizontally, with said warp-threads and weft-threads interwoven to form said pockets with vertical selvage-edged mouths. 45

5. In a carrier, the combination with a supporting-band having upper and lower housing-slits, of an applied pocket open at the side and having upper and lower attaching fins entered into said housing-slits 55 and fastened therein.

6. In a carrier, the combination with a supporting-band having its upper and lower margins split, forming housing-slits, of an applied pocket open at the side and having 60 upper and lower attaching fins which are returned upon themselves, with their returned portions entered into and fastened within said housing-slits.

7. A carrier comprising a band having a 65 projecting pocket with a side-opening, and a retainer flexibly hinged to the pocket-top, extending down past the said side-opening, and fastening detachably to the pocket-bottom.

8. A cartridge-carrier worn in a horizontal position having as worn a series of pockets in line with one another horizontally, said pockets having side-openings and arranged in opposite sets with all the side-openings of the respective sets facing toward 70 the front. 75

In testimony whereof I affix my signature in presence of two witnesses.

FRANK R. BATCHELDER.
